UNITED STATES PATENT OFFICE.

HUGH N. ATKISSON, OF LANSING, WEST VIRGINIA.

BREAD-CUTTER.

1,175,675.

Specification of Letters Patent. Patented Mar. 14, 1916.

Application filed April 23, 1915. Serial No. 23,465.

To all whom it may concern:

Be it known that I, HUGH N. ATKISSON, a citizen of the United States, residing at Lansing, in the county of Fayette and State of West Virginia, have invented new and useful Improvements in Bread-Cutters, of which the following is a specification.

This invention relates to slicing machines and more particularly to bread slicing machines.

One of the principal objects of the invention is to provide a simple and efficient machine of this type wherein slicers of even thickness may be severed from the loaf and wherein after each slice is cut the loaf is automatically fed forward a predetermined distance in position for the cutting of the next slice.

Further objects of the invention will appear as the following specific description is read in connection with the accompanying drawings which form a part of this application and in which:

Figure 1 is a side elevation; Fig. 2 is a top plan view; Fig. 3 is an end elevation showing the parts in one position in dotted lines; Fig. 4 is a horizontal section taken on the line 4—4 of Fig. 3; Fig. 5 is a vertical transverse section taken on the line 5—5 of Fig. 2, and Fig. 6 is a longitudinal section.

Referring more particularly to the drawings, 1 represents an elongated base having a centrally positioned longitudinal groove 2 formed therein for a purpose to be hereinafter described. Secured to the side edges of the base are the side members 3 which have secured thereto the retaining strips 4 separated from the base to produce lateral grooves 5 in which the loaf carrier 6 is adapted to slide. This carrier rests upon the base 1, and has its side edges engaged within the grooves 5 and is normally actuated in one direction by a spiral spring 7 which is fitted within the groove 2 and secured at one end to the forward part of the base and at its opposite end to the rear of the loaf carrier. The carrier 6 is also provided with an abutment 8 against which the end of the loaf is adapted to bear and connected to the abutment and to the carrier 6 is a handle 9 provided for withdrawing the carrier against the tension of the spring 7 and also providing a brace for the abutment.

Secured to the side edges of the base at

the front end of the sides 3 are a pair of uprights 10 connected together at their upper ends by a yoke member 11 and provided with vertical slots 12 in which the knife blade 13 is reciprocally mounted. This knife blade is provided at one end with any suitable type of handle 14 and at its opposite end is pivotally and slidably connected to the lever 15 pivoted in bearings 16 carried by the adjacent upright 10. This lever comprises a yoke shaped head which is pivoted in the bearing 16 and extending outwardly from each end of the head are a pair of separated longitudinally slotted legs 17 between which the knife blade 18 is adapted to travel, a bolt 19 passing through the knife blade and through the slots in legs 17 whereby the lever will be actuated upon the reciprocation of the blade 13. Connected to the outer end of the legs 17 is a connecting rod or bar 20 which is jointed at its opposite end to a cut-off plate or shutter 21 pivoted at one end to one of the up-rights and having its free end guided by a finger 22 secured to the opposite up-right and spaced therefrom.

In order to hold the loaf against the base of the carrier 6 there is adjustably secured to the up-rights, by means of the set screws 23, a yoke member 24 adapted to bear upon the upper face of the loaf as will be readily understood.

The lateral end of the connecting rod 20 is passed through the legs 18 and is threaded to receive an adjusting screw 25 arranged to draw the connecting rod toward the up-right so that the cut-off plate 21 may be always held in proper relation with the up-rights and with the knife and so that it will properly enter the space between the finger 22 and the uprights. As shown the upper end of the finger 22 is preferably beveled to insure the proper entrance of the cut-off plate into the space.

In the operation of the device the carrier 6 is drawn rearwardly a sufficient distance to permit of the loaf being placed between the abutment 8 and the cut-off plate 21 and after the loaf has been placed in such position, is released. The knife plate at this time is elevated to the upper end of the slots 12. Upon being pushed forward the blade will travel downwardly at the same time and through the lever 15 and connecting rod 20 the cut-off plate will be elevated and carried out of the path of the

end of the loaf. When the lever 16 is in horizontal position the knife blade may be drawn back and forth without appreciably effecting the position of the cut-off plate. 5 When the knife is drawn toward the operator to its full extent and raised out of the kerf just made in the loaf the cut-off plate will be lowered into position. The blade, of course, being extended with the bolt 19, 10 engaging the outer wall of the slots in the legs 18, both ends of the blade are then simultaneously elevated, the knife then being drawn toward the operator is released from the loaf permitting it to advance under the action of the spring 7. However, 15 after the knife is drawn toward the operator the cut-off plate will be moved downwardly entering between the severed slice and the end of the loaf and stopping the 20 movement of the loaf, thus placing the same into position where upon the next operation of the knife a similar slice will be severed from the loaf.

What is claimed is:—

25 1. A bread slicing machine comprising a base, a knife mounted for reciprocation

across said base, a pivoted cut-off plate, a slotted lever pivoted to the base, and normally lying at an angle thereto and to the knife, a pivotal and slid able connection between the knife blade and the lever and a rigid connection between the lever and the cut-off blade. 30

2. A bread slicing machine comprising a base, slotted uprights connected to the base, 35 means for connecting the uprights together at their upper ends, a knife reciprocatingly mounted in the uprights across the base, a slotted lever fitted to the base, a bolt passing through the end of the knife and through the slots in said lever, a cut-off plate pivoted to one of the uprights, a finger 40 coöperating with one side of the remaining upright for guiding the upper end of the cut-off plate and a link pivotally connecting the cut-off plate and the lever together. 45

In testimony whereof I affix my signature in presence of two witnesses.

HUGH N. ATKISSON.
